UNITED STATES PATENT OFFICE.

CONSTANT DUHEM, OF DENVER, COLORADO.

MACHINE FOR WASHING, SIZING, AND AMALGAMATING GOLD AND SILVER.

SPECIFICATION forming part of Letters Patent No. 224,406, dated February 10, 1880.

Application filed November 22, 1877.

To all whom it may concern:

Be it known that I, CONSTANT DUHEM, of the city of Denver, county of Arapahoe, and State of Colorado, have invented a new and Improved Gold-Saving Apparatus; and I hereby declare the following to be a full, clear, and exact description thereof, reference being had to the accompanying drawings, making part of this specification, in which—

10 Figure 1 is a longitudinal vertical section of my amalgamator. Fig. 2 is a side elevation. Fig. 3 is a view of the spring riffle-spout.

The object of my invention is to provide a machine for washing and amalgamating gold ores; and it consists, first, in a grated dumping-gate that removes the bowlders from the gravel or ore; secondly, in a series of concentric conical separators provided with screw-conveyers located in a water-tank, and having 15 means of feeding the ore into the conical separators, and discharging-chutes to carry off the different-sized tailings; and, thirdly, in a peculiarly-arranged series of amalgamating-plates, in combination with a series of thin 20 sheets of water forced upward from the bottom, and supplemental plates, which the water passes beneath.

In order that those skilled in the art may make and use my invention, I will proceed to 30 describe the manner in which I have carried it out.

In the said drawings, A is a platform for the reception of the ore or gravel, and is substantially a grate having its bars two inches 35 in width and two and one-half inches apart. Each alternate bar A³ has one end resting on the end of the frame and the other end attached to a revolving cross-bar, P, which is rotated by means of a cam, A², and a lever, 40 A'. This rotation raises the alternate bars A³ to any desired angle and leaves the spaces between the remaining bars open to the extent of seven inches, and all the gravel or ore of less than seven inches in diameter drops into 45 the hopper C, while all over that size is raised by bars A³ and thrown off the grate.

Beneath the grate is a four-sided funnel-shaped hopper, C, to receive the ore.

D is a combined sizer, conveyer, and cylindrical washer, of a conical form, the apex of the cone being farthest from hopper C, and

rotating on a horizontal central shaft, I, having its bearings in standards M M at each end of the platform. This sizer or separator D, which has coarse openings, has a spiral 55 flange, V, from end to end, acting as a screw-conveyer to feed the ore toward the chute O.

Surrounding the cone D is fine-meshed cone E, also having a screw-conveyer, V, interposed between it and cone D, and its lines not parallel to the lines of cone D, the divergence being toward hopper C. The outside cone does not extend the entire length of the inside cone, but only so far as to have its open end over the chute F, into which the coarser particles of gold or sand are dropped. Ruffles 60 transverse the chute F detain the heavy particles of gold, while a shaking motion imparted to the chute by means of a spring-support, n, and projections n' on cone D, which strike as 65 the cone rotates, allows the light sand to float off into F' and pass among the tailings. From cone D into hopper C is a communicating collar, K, through which the ore passes from the hopper into the cone, and, around this collar 70 is a pulley, N, to rotate the cones by means of a driving-belt.

The finest particles of sand and float-gold pass through the meshes of cone E and drop 80 on the amalgamating-plates, which are arranged across the bottom of a water-tank, T, in which the cones are partially submerged. These amalgamating-plates G are one or more feet in height, and are placed so their plates are at right angles to each other and their 85 edges meet at i i', each pair forming a triangle with a portion of the bottom of the tank. Each alternate plate of the series G has over it and raking upward toward the front, and parallel with it, a supplemental plate, r, and 90 between it and the contiguous plate G is forced a stream of water through nozzles H H, constructed so as to project a thin sheet of water upward, as indicated by the arrows. The sand that falls on these diagonal plates, 95 and which would accumulate at the bottom, is kept continually in motion by the streams from nozzles H, by which the sand is thrown upward and finally washed into chute F', while the float gold is freely subjected to the 100 operation of the amalgamating-plates.

Any suitable valve or adjustable opening

can be made to the chute F', so as to control the height of water in the tank.

Having thus described my invention, what I claim as new, and desire to secure by Letters Patent, is—

1. The dump-table consisting of the stationary grates A and the tilting grates A³, lying horizontally with the stationary grates to receive the material, but capable of being tilted to discharge rocks and boulders, substantially as herein described.

2. The hinged tilting grates A³, provided with lever P and connecting-bar, in combination with the hand-lever A', rod B, and cam 15 A², all constructed and operated substantially as set forth.

3. The conical grated or foraminous exterior and interior cylinders D E, rotating upon a common axis, as shown, said cylinders having 20 spiral feeding-flanges around their interior, and constructed to rotate with their larger end in a tank of water, T, substantially as and for the purpose herein described.

4. The apron F, with its transverse ripples supported in the tank T, to receive the material from the outer cylinder, E, and having a 25 tossing motion communicated to it by means

of the spring-support n and projections n' to separate the gold nuggets from the fine gravel, substantially as herein described.

5. The tank T, with its bottom divided into a series of hopper-shaped compartments and provided with amalgamating-plates or partitions G, in combination with nozzles H at the bottom, to project a sheet of water under pressure, and the supplemental amalgamating-plates r, underneath which the water passes, substantially as herein described.

6. A machine for washing gold and silver, consisting of the receiving-platform A, discharge-hopper C, and the concentric cylinders D E, and separating-apron F, in combination with the tank T, having its bottom formed into the hopper-shaped amalgamating-compartments and provided with the directing-plates, 40 to discharge the material from one compartment to the next and to separate the light from the more valuable parts, substantially as herein described.

Denver, Colorado, October 13, 1877.

CONSTANT DUHEM.
